United States Patent Office.

JOHN YOUNG, OF BROOKLYN, NEW YORK.

Letters Patent No. 61,789, dated February 5, 1867.

IMPROVEMENT IN PISTON-ROD PACKING.

The Schedule referred to in these Letters Patent and making part of the same.

Specification of certain improvements in Metallic Packing for Piston-Rods, &c., invented by JOHN YOUNG, of Brooklyn, in the county of Kings, and State of New York.

Nature and Object of the Invention.

My invention has for its object to diminish the friction of the rod in passing back and forth through the packing of the stuffing-box and at the same time to furnish an economical and superior article; and consists of an ordinary hemp or other packing, or its equivalent, enclosed in a net-work of brass wire, as hereinafter more fully described.

Description of the Drawings.

Figure 1 is a longitudinal section of a piston-rod, stuffing-box, gland, and representing my improved packing enclosed in the stuffing-box and pressed down.

Figure 2 is a cross-section of the piston-rod, stuffing-box, and packing, looking to the right of the line *z z*, fig. 1.

Figure 3 is a view of one size of packing.

Figure 4 is a view of a larger size of packing, the wire being loosely netted to show the construction.

Figure 5 is a cross-section of fig. 4.

General Description.

A is the piston-rod; B is the stuffing-box; C is the gland; D is the packing, which is an ordinary hemp packing, covered with brass wire by either winding, weaving, or braiding. The latter construction I prefer. Said packing D is manufactured of various sizes, and sold in lengths to suit purchasers. When used, a sufficient length is cut from the roll to form a ring around the inside of the stuffing-box, as shown in fig. 2. Another length is then cut off and placed within the stuffing-box upon the first ring, care being taken to break joints as indicated by the dotted lines in fig. 2, and so on, according to the depth of the stuffing-box. By the pressure of the gland C the packing D takes the shape represented in fig. 1, or even a rectangular form, if sufficient pressure is applied. The packing should be saturated with tallow or other lubricating substance before being placed in the stuffing-box, the same as other packing.

Among the advantages of this packing are the readiness with which it is fitted to, and inserted in, a stuffing-box of any size; its perfection as a packing completely resisting the passage of steam or water; the very great reduction in the friction; the long time which the packing will wear without being renewed; and the fine polish which its use gives to the rod.

Claim.

I claim a metallic packing formed by enclosing an ordinary hemp or other packing, or its equivalent, in a netting of brass wire, by either winding, weaving, or braiding the enclosing wire around it, substantially as and to the effect described.

JOHN YOUNG.
